UNITED STATES PATENT OFFICE.

WILLIS E. MANN, OF ALLENVILLE, ILLINOIS.

HARVESTER-REEL.

SPECIFICATION forming part of Letters Patent No. 739,692, dated September 22, 1903.

Application filed November 5, 1902. Serial No. 130,177. (No model.)

To all whom it may concern:

Be it known that I, WILLIS E. MANN, a citizen of the United States, and a resident of Alleville, in the county of Moultrie and State of Illinois, have made a certain new and useful Invention in Harvester-Reels; and I declare the following to be a full, clear, and exact description of the same, such as will enable others skilled in the art to which it applies to make and use the invention, reference being had to the accompanying drawings, and to letters of reference marked thereon, which form a part of this specification.

Figure 1 is a central longitudinal section of the reel extended or with the reel-arms unfolded. Fig. 2 is a detail sectional view of the hub *c*. Fig. 3 is an end view of the hub shown in Fig. 2. Fig. 4 is a view similar to Fig. 1 with the reel-arm contracted or folded. Fig. 5 is a section on the line 5 5, Fig. 4. Fig. 6 is a detail end view of hub *c* with collar removed. Fig. 7 is a section on the line 7 7, Fig. 4. Fig. 8 is a detail end view of the collar *v*. Fig. 9 is a plan view of the hub and reel. Fig. 10 is a perspective view of the ring and hub. Fig. 11 is a perspective view of the disk.

The invention relates to folding harvester-reels; and it consists in the novel construction and combinations of parts, as hereinafter set forth.

In the accompanying drawings, illustrating the invention, the letter *a* designates the driving-shaft.

b represents a central hollow reel-shaft, which receives the driving-shaft *a* in its hollow portion, and the two are secured together by means of a pin *k*, usually provided with a spring connection, this hub and the hollow reel-shaft being also secured to the driving-shaft by said pin. This reel-shaft is detachable and is designed to be arranged to fit any binder. The reel-hubs *c c'*, rigidly fixed upon said shaft *b*, are similar, except that one hub *c* is usually made a little longer than the other. The hub is provided with short lug-arms *g*, which extend radially therefrom for the attachment of the reel arms or stays *f*, which are double, each consisting of two

parts, which are pivoted one on each side of the lug-arm *g* by means of the pivot-bolt *m*.

To one side of each hub at its outer portion is bolted a peripheral abutment-ring *d* by means of bolts *n*, which are seated in perforations in the lug-arms. The outside of the ring is flush with the ends of the lug-arms, and the ring is also provided with arc-form bracing-lugs *d'*, which project around the hub between the stays or arms of the reel when unfolded for use in order to hold them firmly in a bracing manner. On the other side of the hub *c* is placed on the shaft a movable locking and bracing disk *e*, which is held in position by means of a collar *h*, which is secured on the shaft by means of a pin or key or other suitable device. This disk is provided with sector-form lugs *p*, which are radially arranged and are separated from each other by an interval *q*, which is a little greater than the thickness of the double-branched stay, which is designed to pass through this interval when the reel is folded. When unfolded to position for use, the stay is turned outward against the abutment-ring and is locked in position by means of a lug *s* on one side of the sector-shaped lug *p*, which when the disk *e* is rotated a little comes into position, engaging the stay. By the same locking-lug *s* when the reel is folded each stay is locked in folded position by turning the disk to bring the lug over the same. The disk is held in locking position by means of a spring bolt or pin *t*, which is seated in bearings of one of the sector-lugs *p* and engages a perforation in the hub. When the reel is to be folded or unfolded, the disk must be moved sufficiently to allow the stays to pass through the narrower portion or throat of the interval between the sector-lugs *p*. The outer hub *c'*, or hub which is farthest from the binder, need not be provided with a movable locking-disk, but should have a small bracing collar or disk attached to the outside of the hub, as indicated at *v*.

The horizontal bars *w* of the reel are designed to be pivoted to the ends of the stay-bars *f* between the branches thereof, as shown, such stay-bars *f* having thus a parallel move-

ment in folding and unfolding. In this manner it is designed to provide for harvesters a strong folding reel which can be readily folded or unfolded and can be secured in either 5 position by the same locking device.

Having described this invention, what I claim, and desire to secure by Letters Patent, is—

1. In a harvester-reel, the central shaft, the 10 hubs rigidly fixed upon said shaft, the folding stays pivoted to said hubs, and rotary means for locking said stays in both folded and unfolded positions, substantially as specified.
- 15 2. In a harvester-reel, the central shaft, the hubs upon said shaft, the folding stays pivoted to said hubs, each said hub having on one side thereof an abutment-ring for the stays, and one of said hubs having on the 20 other side thereof rotary means for locking the stays in position, substantially as specified.
- 25 3. In a harvester-reel, the central shaft, the hubs, upon said shaft, the folding stays pivoted to said hubs, one of said hubs having an

abutment-ring for the stays and arc-form bracing-lugs, and rotary means for locking the stays in both folded and unfolded positions, substantially as specified.

4. In a harvester-reel, the combination with 30 the hub, and the folding stays, of the movable locking-disk, comprising the sector-form lugs having intervals between them wider than the stays, and peripheral locking-lugs projecting in said intervals, substantially as 35 specified.

5. In a harvester-reel, the combination with the detachable hollow shaft, of the double-branched stays, the radially-lugged hub in said shaft, the peripheral bracing-ring on one 40 side of said hub, and the movable locking-disk having passage intervals for said stays, and locking-lugs, and the holding-pin for said hub and disk, substantially as specified.

In testimony whereof I affix my signature 45 in presence of two witnesses.

WILLIS E. MANN.
